[57] CLAIM

The ornamental design for a vacuum cleaner converter,
as shown and described.

DESCRIPTION

FIG. 1 is a left side elevational view of a vacuum
cleaner converter showing our new design, the
elements shown in broken lines are for illustrative purposes
only and form no part of the claimed design;

FIG. 2 is an enlarged left side elevational view thereof,
the right side being a mirror image;

FIG. 3 is an enlarged front elevational view thereof;

FIG. 4 is an enlarged top plan view thereof;

FIG. 5 is an enlarged rear elevational view thereof;

FIG. 6 is an enlarged bottom plan view thereof; and,

FIG. 7 is an enlarged partial cross sectional view taken
along line 7—7 in FIG. 4.
